UNITED STATES PATENT OFFICE.

JOHN H. HINMAN, OF PHOENIXVILLE, PENNSYLVANIA, ASSIGNEE, BY MESNE
ASSIGNMENTS, TO HEINE SAFETY BOILER COMPANY, OF PHOENIXVILLE,
PENNSYLVANIA.

SUPERHEATER CONSTRUCTION FOR BOILERS.

1,304,480.

Specification of Letters Patent.

Patented May 20, 1919.

Application filed April 28, 1917. Serial No. 165,060.

To all whom it may concern:

Be it known that I, JOHN H. HINMAN, a citizen of the United States, residing at Phoenixville, in the county of Chester and

5 State of Pennsylvania, have invented certain new and useful Improvements in Superheater Construction for Boilers, of which the following is a specification.

My invention consists of an improved 10 superheater construction for boilers. One object of my invention is to provide a superheater construction which will be especially adapted for use in connection with water tube boilers.

15 Another object is to provide a water tube boiler with a superheater construction whereby the superheater chamber and superheater will be located in the midst of the space between the water tubes and through 20 which all of the hot products of combustion from the furnace travel.

Another object is to provide the superheating chamber with a damper for regulating the amount of products of combustion passing therethrough, thus regulating the degree 25 and pressure of the superheated steam.

A further object is to provide a novel arrangement of the superheating elements which extend into said chamber and thus 30 cause the steam passing therethrough to be effectively heated.

A further object of my invention is to so arrange the controlling damper for the superheating chamber that it will not be engaged by the products of combustion until 35 they have passed through the superheating chamber where their heat will be less intense. Hence, I am able to use a cast iron or other metallic damper for the controlling purposes 40 above enumerated.

These objects, and other advantageous ends which will be described hereinafter, I attain in the following manner, reference being had to the accompanying drawings in 45 which

Figure 1 is a longitudinal section through a water tube boiler having my invention illustrated in connection therewith, the water legs, tubes, and drum being shown in outside view.

Fig. 2 is a section on the line 2—2 of Fig. 1.

Fig. 3 is an elevation with the side wall

of the boiler casing removed and showing in outside view the headers of the super- 55 heater.

Fig. 4 is a fragmentary section taken on the line 4—4 of Fig. 1.

Fig. 5 is a face view of an elongated steel superheater header which forms a part of 60 my invention.

Fig. 6 is an enlarged section on the line 6—6 of Fig. 5.

Figs. 7 and 8 are face views of sectional superheater headers which form a part of my 65 invention, the header shown in Fig. 8 being longer than the header shown in Fig. 7.

Fig. 9 is a sectional view of similar nature to Fig. 1 showing a modification in the arrangement of the baffling and the consequent 70 change of position of the regulating damper.

Referring to Figs. 1 to 8 inclusive of the drawings, 1 represents a water tube boiler having a main drum 2, water legs or headers 3 and 4, and tubes 5 which connect with the water legs. The water legs 3 and 4 are supported by the casing 6, the side walls 7 and 8 of the casing being illustrated in Fig. 2.

The wall 7 has an opening 9 in which is 80 fitted the elongated superheater headers 10, 11, and 12. These headers extend lengthwise of the boiler, the header 10 being made endless and mounted directly above the sectional headers 11 and 12. The sectional 85 header 11 is longer than the header 12 for a purpose hereinafter more fully described and the header 10 is of a length slightly less than the combined lengths of the headers 11 and 12. 90

The headers 11 and 12 are open at their oppositely disposed ends and closed at their abutting ends as clearly shown in Fig. 3. All of said superheater headers, as illustrated in Fig. 3, take the angle of inclination 95 of the water tubes 5.

All of the headers 10, 11, and 12, have superheating pipes 13 communicating therewith, said superheating pipes each being U-shape and extending transversely into a 100 superheating chamber 14 which is formed in the midst of the tubes 5 as clearly shown in Fig. 2.

The pipes 13 each has one of its ends connecting the header 10 and its other end communicating with either of the headers 11 or 105

12 according to the position of the superheating pipe within the length of the headers. By this arrangement the steam to be superheated and which enters the end 15 of 5 the header 12, will pass through the header 12 and through the ends of the pipes 13 which communicate therewith into the lower end of the header 10. From thence it will pass upwardly and longitudinally of the 10 header 10 and through other pipes 13 into the header 11, where it will be taken off as superheated steam through the open end 16 of the header 11.

The superheating chamber 14 is formed 15 by a baffle produced by tiles a portion of which is mounted on the row of the tubes 5 which is directly above the space included in the chamber 14. This baffle portion 17 extends on an incline downwardly from the 20 water leg 3 and stops short of the water leg 4 so as to leave a space between its ends and the water leg 4 to permit the products of combustion to pass to the uppermost tubes and to the drum 2 as will hereinafter be 25 more fully described.

Another portion 18 of said baffle extends downwardly from the water leg 3 and stops short of the water leg 4 in a manner similar to the baffle portion 17. A short upright or 30 vertical portion 19 of said baffle (see Fig. 2) extends upwardly from the baffle 18 to the baffle 17. This short vertical portion 19 of said baffle also leads downwardly from the water leg 3 and stops short of the water 35 leg 4 in a manner similar to that described in connection with the baffle portions 17 and 18. Thus, the portions 17, 19, and 18 form a baffle wall which extends entirely across the width of the boiler casing and provides 40 the top and a portion of the end of said superheater casing 14.

Another portion 20 of said baffle forms the bottom of the superheating chamber 14 and extends from the wall 7 of the boiler casing 45 to the baffle portion 19. However, this baffle portion 20 is positioned entirely within the length of the space between the water legs 3 and 4 so that a passage is provided at both ends. This is clearly illustrated in 50 Fig. 1.

A grate 21 providing the furnace is mounted between the front wall and an intermediate wall 22 of the casing and directly under the forward end 23 of the baffle portion 20 so that the products of combustion arising from the furnace engage the forward portion 24 of the baffle portions 17, 19, and 18, and are compelled to pass through the superheating chamber 14. After passing 55 through the superheating chamber, the products of combustion pass upwardly and forwardly in the direction of the arrows to heat the tubes 5 which are above said baffle portions 17, 19, and 18.

60 65 A baffle 25 is interposed between the tubes

5 and the drum 2, said baffle extending from the water leg 4 forwardly and stopping short of the water leg 3 so as to provide a passage 26 through which the products of combustion pass to heat the drum 2 prior to passing 70 through the outlet opening 27.

A damper 28 is provided at the rear end of the superheating casing 14 and may be moved on its pivot 29 by a rod 30 which extends to the outer part of the side wall 7. 75 The rod 30 is preferably provided with a handle 31 so that the damper may be swung on its pivot to regulate the amount of the products of combustion passing through the superheating chamber 14.

Furthermore, I preferably provide the damper at the outlet end of the chamber 14 so that the intensity of the heat of the products of combustion passing through the superheating chamber will be reduced prior to 80 engaging the damper, thus I am able to use a comparatively thin damper and one made of cast iron if desired.

In the form of my invention shown in Fig. 9, I have shown an additional baffle 32 90 which extends rearwardly from the front water leg 3 stopping short of the rear water leg to provide a passage 33 for the products of combustion prior to passing forwardly between the water tubes and through the 95 superheating chamber.

It will be further noted that in this modification that instead of having the baffle portions 17, 19, and 18 extend rearwardly from the water leg 3, they extend forwardly 100 from the water leg 4 and all stop short of the water leg 3 to provide a passage for the products of combustion upwardly between the tubes. With this construction, the products of combustion pass inwardly at the 105 rear end of the superheating chamber 14, and the damper 28 is located at the forward end of the superheating chamber so that in this instance also the products of combustion passing through the superheating chamber 110 will be less intense at the outlet end of the superheating chamber than at the inlet end and I can use a comparatively thin regulating damper as above described in connection with the form illustrated in Figs. 1 to 4 inclusive.

Also, it will be noted that in Fig. 9 I have shown the baffle 25 extending rearwardly from the front water leg 3 so that after the products of combustion pass 120 through the superheating chamber, they will be compelled to travel rearwardly between the uppermost tubes 5 and through the opening provided between the end of the baffle 25 and the water leg 4.

In the sectional views shown in Figs. 1 and 9, I have not shown the water legs in section, but it will be understood that these water legs are hollow and communicate with the hollow drum 2 and with the water tubes 130

5. By arranging the superheating chamber and superheater in the midst of the tubes 5, between which all of the products of combustion pass prior to reaching the outlet passage 27, a high pressure and degree of superheat can be obtained.

Furthermore, the superheater can be readily removed from the superheating chamber 14 by pulling it out of the opening 9 or the pipes of the superheater can be cleaped without removing the superheater from the chamber 14. To accomplish this latter end, each of the headers 10, 11, and 12, has holes 34 which are in alinement with the ends of the superheating pipes 13, and these holes 34 are normally closed by threaded plugs 35. Thus, my invention is extremely practical, both as a means for securing superheated steam under a desired pressure and temperature and also as a means which permits the ready removal or cleaning of any of the several parts.

By making the sectional header 11 longer than the sectional header 12, additional space for expansion of the superheated steam is provided and the superheated steam will freely pass from one header to the other through superheating pipes 13.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

1. A boiler including a casing, two headers, a plurality of superimposed rows of tubes connecting said headers within the casing, a baffle interposed between certain of the rows of tubes, said baffle having two portions spaced apart, one above the other, and extending partway of the length of the tubes, the upper one of said portions having a part extending lengthwise beyond the adjacent end of the lower portion to prevent the products of combustion from passing directly from the fire box of the casing to the uppermost of said tubes, said portions of the baffle extending transversely from one side wall of the casing toward the opposite side wall of the casing and stopping short thereof, said baffle also having an upright portion extending lengthwise of the tubes and between said first and second portions, said third mentioned portion being spaced between said side walls of the casing, another baffle portion bridging the space between said upright portion and said opposite side wall of the casing, and a superheater extending inwardly from said first mentioned

side wall and between said first two portions of the baffle, substantially as described.

2. A boiler including a casing, two headers, a plurality of superimposed rows of tubes connecting said headers within the casing, a baffle interposed between certain of the rows of tubes, said baffle having two portions spaced apart, one above the other, and extending partway of the length of the tubes, the upper one of said portions having a part extending lengthwise beyond the adjacent end of the lower portion to prevent the products of combustion from passing directly from the fire box of the casing to the uppermost of said tubes, said portions of the baffle extending transversely from one side wall of the casing toward the opposite side wall of the casing and stopping short thereof, said baffle also having a portion extending lengthwise of the tubes and between said first and second portions, said third mentioned portion being spaced between said side walls of the casing, and a superheater extending inwardly from said first mentioned side wall and between said first two portions of the baffle, said baffle having another portion bridging the space between the third mentioned portion and said opposite side wall of the casing, said fourth mentioned portion extending partway of the length of said tubes and permitting a portion of the products of combustion arising from the fire box to pass to the uppermost tubes without passing through the space including the superheater, substantially as described.

3. A boiler including a casing, two headers, a plurality of superimposed rows of tubes connecting said headers within the casing, a baffle interposed between certain of the rows of tubes, said baffle having two portions spaced apart, one above the other, and extending partway of the length of the tubes, the upper one of said portions having a part extending lengthwise beyond the adjacent end of the lower portion to prevent the products of combustion from passing directly from the fire box of the casing to the uppermost of said tubes, said portions of the baffle extending transversely from one side wall of the casing toward the opposite side wall of the casing and stopping short thereof, said baffle also having an upright portion extending lengthwise of the tubes and between said first and second portions, said third mentioned portion being spaced between said side walls of the casing, another baffle portion bridging the space between said upright portion and said opposite side wall of the casing, a superheater extending inwardly from said first mentioned side wall and between said first two portions of the baffle, and another baffle spaced above said first mentioned baffle to cause the products of combustion to pass

longitudinally above the first mentioned baffle to heat the uppermost tubes, substantially as described.

4. A boiler including a casing, two headers, a plurality of superimposed rows of tubes connecting said headers within the casing, a baffle interposed between certain of the rows of tubes, said baffle having two portions spaced apart, one above the other, 10 and extending partway of the length of the tubes, the upper one of said portions having a part extending lengthwise beyond the adjacent end of the lower portion to prevent the products of combustion from passing 15 directly from the fire box of the casing to the uppermost of said tubes, said portions of the baffle extending transversely from one side wall of the casing toward the opposite side wall of the casing and stopping short 20 thereof, said baffle also having a portion extending lengthwise of the tubes and between said first and second portions, said third mentioned portion being spaced between said side walls of the casing, a super- 25 heater extending inwardly from said first mentioned side wall and between said first two portions of the baffle, said baffle having another portion extending between the third mentioned portion and the second mentioned 30 side wall of the casing, said fourth mentioned portion extending partway of the length of said tubes and permitting a portion of the products of combustion arising from the fire box to pass to the uppermost tubes without passing through the sides including the superheater, and a 35 damper adapted to close the space between said first two portions of the first mentioned baffle, substantially as described.
5. A boiler including a casing, headers

positioned adjacent the front and rear of said casing, a plurality of superimposed rows of water tubes connecting said headers, a baffle interposed between certain of the rows of tubes, said baffle having two portions spaced apart, one above the other, one of said portions extending from one of the headers toward the other of said headers but stopping short of said latter mentioned header to provide a passage upwardly for 50 the products of combustion, the other portion of said baffle having its front and rear edges spaced from the adjacent headers to provide passages upwardly for the products of combustion, said baffle also having 55 a portion extending lengthwise of the tubes between said first two portions, said third mentioned portion being spaced between said side walls of the casing, and a superheater extending inwardly from said first 60 mentioned side wall and between said first two portions of the baffle, said baffle having another portion extending between the third mentioned portion and the second mentioned side wall of the casing, said fourth mentioned portion extending at one end into close proximity to said first mentioned header and having its opposite end spaced from the other of said headers to permit a portion of the products of combustion to 70 pass to the uppermost tubes without passing through the space including the superheater, substantially as described.

In testimony whereof I have signed my name to this specification in the presence of 75 two subscribing witnesses.

JOHN H. HINMAN.
